UNITED STATES PATENT OFFICE.

JOSEPH TETLOW, OF SACO, MAINE, ASSIGNOR TO HERBERT R. JORDAN,
OF SACO, MAINE.

TROLLEY.

No. 824,833.

Specification of Letters Patent.

Patented July 3, 1906.

Application filed November 7, 1904. Renewed January 19, 1906. Serial No. 296,828.

To all whom it may concern:

Be it known that I, JOSEPH TETLOW, a subject of the King of Great Britain, residing at Saco, in the county of York and State of Maine, have invented new and useful Improvements in Trolleys, of which the following is a specification.

My invention relates to improvements in trolleys, and more particularly to the construction of the running contact and in the method of mounting it in the harp. Its objects, among others, are to make the trolley more durable, to lessen the friction of the wearing parts, to enable the contact to accommodate itself to changes in the direction and the altitude of the track, and to render it possible to replace the center or part of the contact most subject to wear without at the same time renewing the sides.

In the drawings herewith accompanying and making a part of this application, Figure 1 is a vertical transverse sectional view of my improved trolley. Fig. 2 is a side view of the central member of the running contact. Fig. 3 is an inside view of one of the side members of the running contact. Fig. 4 is a detail plan view showing one method of securing the ends of the harp to the body thereof, and Fig. 5 is an end view of the core which supports the running contact.

Same characters refer to like parts in all the figures.

In said drawings, A represents the body of the harp, and B the terminals, removably secured thereto in any convenient manner—as, for example, by threaded bolt C passing through the body of the harp and an extension D of the terminals. It is important that the extremities of the harp should be firmly but removably secured to the body, for the reason hereinafter set out. To this end the extension of the terminals is provided with raised sides E, forming a groove or recess F, in which the ends of the body part lie, substantially as shown in Figs. 1 and 4. The headed bolt which secures the terminals to the body of the harp is locked against rotation by means of a flat spring G, secured to the body of the harp by a screw J', said screw passing through an elongated slot J in the spring. The opposite end of the spring is provided with a rectangular opening I, adapted to give entrance to the headed bolt which secures the terminals to the body of

the harp. The terminals are provided on 55 the inside with shanks K and with antifriction ball-races L. They are also centrally bored to receive the threaded end of a bolt M. Mounted upon the shanks of the terminals are rotary disks N, having on the out-sides antifriction-ball-receiving races O to 60 cooperate with the races in the terminals in containing antifriction ball-bearings P. The inner faces of said disks have recesses Q to give entrance to the ends S of a core R, adapted to rotate with said disks, and as a convenient method of removably securing the core to the disks, so as to enable them to be readily separated when desired, the recess Q is 65 rectangular, and the ends of the core are rec- 70 tangular to fit the recess. The core has a rounded section T intermediate its ends and also has on the surface thereof one or more thin projections or lugs U. The running contact is composed of a central wearing-section V with projections W extending outwardly from the sides thereof and preferably has a curved groove X in the periphery thereof at the point of normal contact with the track. The side members Y have openings Y' in the sides thereof to give entrance to the projections W on the central section, whereby the sections are removably interlocked when in the position shown in Fig. 1. 75 The extremities of the outer sections are 80 slightly flaring, as shown at Z. The bores of the several sections are curved, as seen at 1, the curvature being substantially that of the rounded center of the core, whereby the running contact is free to assume a varying angle 90 to the core. The inner section is provided with recesses 2 to give entrance to the lugs U on the core, so as to hold the running contact from rotation independent of the core, but at the same time leave the contact free to assume a varying angle to the core. Interposed between the sides of the running contact and the disks before referred to are coil-springs 3. These coil-springs are for convenience seated one end in a circular groove 4 in 95 the side of the running contact and the other end in a similar groove 5 in the face of the disk, and they tend to hold the parts of the contact in yielding engagement.

It will be obvious that many of the parts 105 may be varied and still be within the spirit and scope of my invention.

To construct my improved trolley, the cen-

tral section of the running contact is first placed in position. The sides of the running contact are then placed in position. Next the springs are placed in position against the 5 side sections of the contact. The disks are then placed in position, after which the terminals with the ball-bearings in the races are screwed onto the ends of the bolt which holds the terminals. The terminals are then set 10 cured to the body of the harp.

The advantages of my improved trolley are that the parts wear longer, run more easily, and accommodate themselves more readily to curves and switches in the track. 15 The liability of the trolley to leave the track is lessened by reason of the fact that the side members of the running contact are free to move one relative to the other, being yieldingly held by the springs.

20 Having thus described my invention and its use, I claim—

1. In a trolley, in combination, a harp comprising a body part and ends removably secured thereto, said removable ends being 25 provided with ball-bearings in the adjacent sides, a running contact comprising a plurality of vertical sections, means for holding the sections in yielding contact and means intermediate said contact and bearings for supporting said running contact.

2. In a trolley, in combination, a harp having ball-bearings in the adjacent sides of its ends, a running-contact support comprising disk with antifriction - ball - receiving 35 races on the outside and core-receiving re-

cesses on the inside, a core having a rounded center and ends adapted to enter and lock in the recesses in said disks and a running contact comprising a plurality of vertical sections mounted upon said rounded portion of 40 the core, the bore of the sections substantially corresponding with the curvature of said rounded portion of the core.

3. In a trolley, a harp having ball-bearings in the adjacent sides of its ends, a running-contact support comprising disks with antifriction-ball-receiving races on the outside, core-receiving recesses on the inside and coil-spring-receiving recesses on the inside and a core having an enlarged rounded center and 45 ends adapted to enter and lock in the core-receiving recesses in said disks, a running contact comprising a plurality of sections mounted upon said enlarged portions of the core, the bore of the sections substantially 50 corresponding with the rounded center of the core, coil-springs interposed between the sides of the running contact and said disks and means for locking the running contact against rotation on the core, said running contact being free to move laterally upon 55 said core.

In testimony whereof I have signed my name to this specification, in presence of two subscribing witnesses, this 31st day of October, 1904.

JOSEPH TETLOW.
